UNITED STATES PATENT OFFICE.

ERNEST R. BURKEY, OF CLEVELAND, OHIO.

PAPER-HANGING DEVICE FOR CEILINGS.

Application filed May 16, 1925. Serial No. 30,648.

The present invention relates to a paper hanging device, and has for its object to provide a device of this character which embodies novel features of construction, where-
5 by it can be used to advantage for applying paper, sanitos or any other wall covering to the ceiling of a room.

Further objects of the invention are to provide a paper hanging device by means of which very wide strips of a wall covering can be readily applied to the ceiling, thereby reducing the number of seams and enabling a neater and more attractive piece of work to be done.

15 The invention further contemplates the provision of a paper hanging device of this character which is comparatively simple and inexpensive in its construction, which can be readily transported from place to place, 20 which is adjustable to different ceiling heights, and which can be readily manipulated by a single operator.

One particular embodiment of the invention has been shown and described in detail for illustrative purposes, although it will be understood that many modifications and changes can be made in the details of construction without departing from the spirit of the invention.

30 For a full understanding of the invention reference is to be had to the following description and accompanying drawings in which—

Figure 1 is a side elevation of a paper hanging device which is constructed in accordance with the invention.

Figure 2 is a front elevation of the standard and main roller with the auxiliary frame removed.

40 Figure 3 is an elevation of the auxiliary frame and roller.

Figure 4 is an enlarged transverse sectional view through the arm of the auxiliary frame, taken on the line 4—4 of Figure 1.

45 Figure 5 is an enlarged end view of one of the rollers, showing the openings which are adapted to be engaged by a locking pin to hold the roller against rotation.

50 Figure 6 is an enlarged detail view of the clamping bar which is used for securing the wall covering to the roller of the auxiliary frame.

Corresponding and like parts are referred to in the following description and indicated on all of the views of the drawing by like reference characters.

Referring to the drawings, the reference character A designates the standard which is mounted upon a base B and provided at its upper end with a main roller C. The standard comprises a lower tubular section 1 and an upper section 2 which telescopes within the lower section. The upper section is provided with a longitudinally extending rack 3 which slides within a corresponding guide channel 4 which is formed in connection with the lower tubular section 1. The two sections of the standard are thereby held against relative rotation and the rack 3 is engaged by a pinion 5 on a shaft 6 which is suitably journaled upon the lower section 1 of the standard. A finger piece 7 is fitted upon the end of the shaft 6 and provides a means for turning the pinion to move the upper section 2 of the standard up or down. The height of the standard can thus be adjusted to the particular ceiling which is being operated upon, and the frictional engagement between the parts is such that the upper section 2 of the standard will remain in an adjusted position without the need of any special locking mechanism for that purpose.

The lower end of the standard is hingedly connected to the base B by means of a hinge 8 which is applied to one side thereof. The standard is thus enabled to be swung downwardly so that it will assume a substantially horizontal position and rest upon the floor, and a suitable latch member 9 is provided for locking the standard in an upright position. This latch may be of any conventional form, although it is shown as mounted upon the base and arranged to engage a lug 10 on the standard. A suitable spring may be provided for holding the latch yieldably in operative position.

The upper end of the standard is provided with a tubular guide member 11 and a roller frame 12 is slidably mounted therein. The cross bar of the roller frame is provided with a rack 13 which is engaged in the usual manner by a pinion upon a shaft 14 which is provided with a handle 15. With this arrangement it will be obvious that by manipulating the handle the pinion can be rotated to slide the roller frame back and forth within the tubular guide 11. The main roller C is journaled between the arms of the roller frame and normally assumes a horizontal position. This roller may be of any desired length and it is intended that the roller shall be sufficiently long to ac-

commodate wall coverings which are made in strips having a considerable width, since it is desirable to use wide strips and reduce the number of seams on the ceiling.

5 The end of the roller is formed with a disc 16 having an annular series of openings 17 therein, any one of said openings being adapted to be engaged by a pin 18 to lock the roller against rotation. The pin 10 is slidable within one of the arms of the roller frame and can be readily drawn outwardly to release the roller or moved inwardly to engage the roller. This is merely a convenient way of locking the roller 15 against rotation, although any desired mechanism can be utilized to accomplish this result.

An auxiliary frame is used in connection with the main frame or standard. The auxiliary frame comprises an arm D which is provided at the outer end thereof with a roller frame 19 upon which the auxiliary roller E is journaled. The auxiliary roller has the same length as the main roller, and 20 is provided with the same means whereby it can be locked against rotation when desired. The arm D of the auxiliary frame comprises the telescoping sections 20 and 21, the outer section 20 being slidable within 25 the end of the inner section 21 so that it can be moved in or out with respect thereto to vary the length of the arm if such is necessary. A set screw 23 is provided for locking the outer section in an adjusted position.

The roller frame 19 of the auxiliary frame is slidably mounted so that it can be moved laterally back and forth to accurately position the wall covering in the desired manner.

40 The roller frame is shown as provided with a rack 35 which is engaged by a pinion on a shaft 36, said shaft being provided with the usual handle 37.

A bell crank lever 38 is arranged in such 45 a manner that one of the arms thereof can engage the nose of the detent 9 to swing the same outwardly into inoperative position. The other arm of the bell crank lever 38 is suitably connected as by means of a wire 39 50 to a finger lever 40 which is pivotally mounted upon the upper end of the lower section 1 of the standard. This arrangement enables the detent to be released by an operator who is standing on a platform and 55 engaged in applying the wall covering to the ceiling.

The inner section 21 of the arm D is formed with a longitudinally extending under-cut or T-shaped slot 24, said slot opening 60 through the extremity of the arm and being provided at one side thereof with a series of notches 26. This slot is adapted to receive a headed stud 25 which projects from one side of the standard. The head of the 65 stud operates within the undercut base of

the slot and serves to hold the arm D against the side of the standard, while the stud may engage any selected one of the notches 26 in the side of the slot to hold the arm against longitudinal movement upon the stud.

70 A suitable cord engaging member such as a hook 27 is applied to the outer end of the arm D and one end of a cord 28 is detachably connected thereto. The other end of the cord extends around a guide pulley 29 which is suitably journaled in the upper end of the standard and has a weight 30 connected thereto. This weight hangs at one side of the standard and serves to counterbalance the arm and swing the same upwardly to bring the roller E into engagement with the ceiling H when the arm is in position. It will be understood that the auxiliary arm D can be quickly connected to the main frame or disconnected therefrom, as may be 80 necessary or desirable in the operation of the device.

85 The strip of wall covering F which is to be applied to the ceiling is first placed upon a paste table and provided with paste 90 in the usual manner, after which the ends can be folded up if desired. The standard may then be placed in position with the hinged side thereof away from the end wall, and the latch 9 may be released and the 95 standard swung downwardly upon the floor. The folded and pasted strip of wall covering is then placed across the main roller C, being preferably handled with a stick where a wide width of wall covering is being 100 handled. With the roller C locked the standard can be swung upwardly into an upright position, and the height thereof adjusted 105 to bring the roller C near the ceiling H but not in contact therewith. The end of the folded strip nearest the end wall may then be unfolded and the strip adjusted upon the main roller so that the proper length thereof is hanging from the roller on the side toward the end wall to cover the 110 portion of the ceiling between the main roller C and the end wall.

115 The auxiliary frame is then brought into operation and the roller E thereof caused to engage the wall covering at a point toward the end thereof. The wall covering is securely clamped against the roller E by means of a spring clamping bar 41, said bar being formed of spring metal and preferably having a bowed formation, as indicated by Figure 6. The ends of the bar are provided with lateral arms 42 having lugs 43 at the extremities thereof. These lugs are adapted to be brought into engagement with openings 44 in the side arms of the roller frame 19, thereby detachably securing the clamping bar in position and causing the same to hold the wall covering against the roller. The bowed formation of the bar insures 120 proper clamping action thereof, and it will 125 130

be understood that the bar can be quickly placed in position or removed therefrom, as may be desired. With the roller E locked against rotation and the wall covering clamped thereagainst the arm D of the auxiliary frame is lifted into position and the T-shaped slot 24 thereof caused to engage the headed stud 25. The stud 25 may be caused to engage a suitable one of the notches 26, depending upon the height of the ceiling, and the cord 28 may then be connected to the hook 27, whereupon the weight 30 will swing the arm upwardly and bring the roller E thereof against the ceiling. Having previously drawn a line in the usual manner the correct distance from the side wall the edge of the strip of wall covering is brought into position as near the line as possible, and when applying the first strip the edge of the wall covering should overhang the end of the roller a sufficient amount to provide for the free passage of the roller along the ceiling and provide for the lap on the side wall which is necessary to take care of any irregularities in the plaster.

The operator may now take his smoothing brush and brush the end which is hanging from the auxiliary roller toward the end wall, thereby applying it to the portion of the ceiling between the auxiliary roller and the end wall. With the clamping bar 41 released and the auxiliary roller E unlocked so that it will rotate freely, the lower end of the auxiliary arm D is moved downwardly a slight amount to disengage the stud 25 from the notch 26, whereupon the auxiliary roller E can be caused to move along the ceiling toward the main roller C. When the two rollers are thus brought into close proximity with each other the stud 25 can be engaged with another of the notches 26 to support the auxiliary frame and leave the operator with both hands free. The detent 9 is now released and, if the operator is standing upon a platform, this can be readily done by a simple manipulation of the finger lever 40 at the upper end of the lower section 1 of the standard. The cord 28 can now be disengaged from the hook 27 and the standard swung downwardly about the hinge connection 8 with the base B, the roller C thereof having been previously unlocked so that it can rotate freely. The downward movement of the standard can be controlled by the operator, who maintains a grip on the cord 28. When the standard has come to rest upon the floor the cord 28 is allowed to run through the pulley until the weight 30 rests upon the floor. The arm of the auxiliary frame may now be grasped in both hands and the auxiliary roller run along the ceiling to the end of the room, thereby applying the strip of wall covering to the full length of the ceiling.

After this the operator may use the smoothing brush on the wall covering in the usual manner and this operation is repeated for the successive strips of wall covering which are applied to the ceiling.

Having thus described my invention what I claim as new and desire to secure by Letters Patent, is,

1. A device for applying wall covering to a ceiling, including a pair of cooperating paper supporting elements, members carrying the paper supporting elements and having a pivotal connection with each other, and a counter balancing connection between the said members.

2. A device for applying wall covering to a ceiling, comprising a standard, paper supporting means thereon, a swinging arm carried by the standard, cooperating paper supporting means on the swinging arm, and a counter-balancing connection between the swinging arm and the standard.

3. A device for applying a wall covering to a ceiling, comprising a standard, a main roller thereon, an arm pivotally supported by the standard and arranged at an inclination thereto, counterbalancing connection between the upper end of the arm and the standard, and an auxiliary roller carried by the arm and arranged for cooperation with the main roller to support a strip of wall covering.

4. A device for applying a wall covering to a ceiling, comprising a standard, a main paper supporting element thereon, an arm arranged at an inclination to the standard and having the end thereof pivotally connected to the standard, a pulley on the standard, a cord connected to the arm and passed around the pulley, a weight applied to the cord for counterbalancing the arm, and an auxiliary paper supporting element carried by the arm and arranged for cooperation with the main paper supporting element to support a strip of wall covering.

5. A device for applying a wall covering to a ceiling, comprising a standard, a main paper supporting element thereon, an arm having the end thereof connected to the standard, a pulley on the standard, a cord passing around the pulley, means for detachably connecting one end of the cord to the arm, a weight applied to the opposite end of the cord for counterbalancing the arm, and an auxiliary paper supporting element carried by the arm and arranged for cooperation with the main paper supporting element to support a strip of wall covering.

6. A device for applying a wall covering to a ceiling, comprising a standard, a main paper supporting element thereon, a stud projecting from the standard, an arm having a slotted portion adjustably receiving the stud, a counterbalancing connection be-

tween the upper end of the arm and the standard, and an auxiliary paper supporting element carried by the arm and arranged for cooperation with the main paper supporting element to support a strip of wall covering.

7. A device for applying a wall covering to a ceiling, comprising a standard, a main paper supporting element thereon, a stud 10 projecting therefrom, an arm formed with a slot slidably receiving the stud and having notches at the sides thereof to interlock with the stud to hold the arm in an adjusted position, and an auxiliary paper 15 supporting element carried by the arm and arranged for cooperation with the main paper supporting element to support a strip of wall covering.

8. A device for applying a wall covering 20 to a ceiling, comprising a standard, a main paper supporting element thereon, a headed stud projecting therefrom, an arm formed with an undercut slot slidably receiving a headed stud and having notches at the side 25 of the slot to interlock with the stud and hold the arm in an adjusted position, a counterbalancing connection between the upper end of the arm and the standard, and an auxiliary paper supporting element carried by the arm and arranged for cooperation 30 with the main paper supporting element to support a strip of wall covering.

9. A device for applying a wall covering to a ceiling, including a base adapted to rest 35 upon the floor when the device is in operation, a standard hingedly connected to the base so that it can be swung downwardly toward the floor, means for locking the standard in an upright position, and means 40 upon the standard for supporting a strip of wall covering.

10. A device for applying a wall covering to a ceiling, comprising a base adapted to rest upon the floor when the device is in 45 operation, a standard hingedly connected to the base and adapted to be swung downwardly toward the floor, means for locking the standard in an upright position, and a roller upon the standard for supporting a 50 strip of wall covering.

11. A device for applying a wall covering to a ceiling, including a base, a standard hingedly connected to the base, means for locking the standard in an upright position, 55 a roller upon the standard for supporting a strip of wall covering, and means for locking the roller against rotation.

12. A device for applying a wall covering to a ceiling, including a standard, a roller 60 frame slidably mounted thereon, a roller carried by the roller frame, means for sliding the roller frame into an adjusted position, and means cooperating with the roller frame to support a strip of wall paper.

13. A device for applying a wall covering

to a ceiling, comprising a standard having a transverse guide at the upper end thereof, a roller frame including a cross bar which is slidably mounted within the guide, a roller journaled upon the roller frame, and means for sliding the frame into an adjusted position.

14. A device for applying a wall covering to a ceiling, including a standard formed in telescoping sections, means for manipulating 75 the sections to adjust the height of the standard, a laterally disposed guide member at the upper end of the standard, a roller frame having a bar slidably mounted within the guide-way, a roller journaled upon the 80 frame, and means for sliding the roller frame to obtain the desired lateral adjustment of the roller.

15. A device for applying a wall covering 85 to a ceiling, comprising a standard, a main roller carried by the standard, an arm detachably connected to the standard, an auxiliary roller carried by the arm and arranged for cooperation with the main roller to support a strip of wall covering, and means for locking the rollers against rotation.

16. A device for applying a wall covering to a ceiling, comprising a standard formed in telescoping sections which are adjustable 95 to regulate the height of the standard, a main roller on the standard, an arm formed in telescoping sections which are adjustable to regulate the length of the arm, means for detachably connecting one of the sections of the arm to the standard, a counter balanced connection between the other section of the arm and the standard, and an auxiliary roller carried by the arm and arranged for cooperation with the main roller to support a 100 strip of wall covering.

17. A device for applying a wall covering to a wall, including a base adapted to rest upon the floor when the device is in operation, a standard hingedly connected to the base so that it can be swung downwardly 110 toward the floor, means for locking the standard in an upright position, paper supporting means at the upper end of the standard, and means for enabling the standard to be supported while it is swung downwardly.

18. A device for applying a wall covering to a wall, including a base adapted to rest upon the floor when the device is in 115 operation, a standard hingedly connected to the base and adapted to be swung downwardly toward the floor, means for locking the standard in an upright position, paper supporting means carried by the standard, an arm carried by the standard, and cooperating paper supporting means on the arm.

19. A device for applying a wall covering to a wall, including a base adapted to rest 120 upon the floor when the device is in opera-

- tion, a standard hingedly connected to the base and adapted to be swung downwardly toward the floor, means for locking the standard in an upright position, paper supporting means upon the standard, a swinging arm carried by the standard, cooperating paper supporting means on the swinging arm, and a counterbalancing connection between the swinging arm and the standard.
- 5 20. A device for applying a wall covering to a wall, including a base which is adapted to rest upon the floor when the device is in operation, a standard projecting from the base and formed in adjustably connected sections so that the length of the standard can be varied, a frame slidably mounted upon the upper end of the standard for lateral adjustment thereon, and paper supporting means upon the frame.
- 10 21. A device for applying wall covering to a wall, including a base adapted to rest
- 15 upon the floor when the device is in use, a standard projecting from the base and hingedly connected thereto, so that it can be swung downwardly toward the floor, means for locking the standard in an upright position, a frame slidably mounted upon the upper end of the standard so that it can be moved laterally relative thereto, and paper supporting means on the frame.
- 20 22. A device for applying a wall covering to a wall, including a standard, a frame slidably mounted upon the standard for lateral adjustment relative thereto, paper supporting means on the frame, an auxiliary arm carried by the standard, a frame slidably mounted upon the auxiliary arm for lateral adjustment relative thereto, and cooperating paper supporting means carried by the frame of the auxiliary arm.

In testimony whereof I affix my signature.

ERNEST R. BURKEY.
